UNITED STATES PATENT OFFICE

ARTHUR C. GAYNOR, OF STRATFORD, CONNECTICUT

SNAP SWITCH

Application filed March 23, 1927. Serial No. 177,679.

This invention relates to electric snap switches and particularly to switches of the character disclosed in my pending application Serial No. 126,530.

5 One object contemplated in the present instance is the provision of means for actuating the circuit making and breaking elements which may be produced at a comparatively low cost and which can be easily 55 assembled in the completed switch.

10 Generally, in snap switches of the present type, there is a handle which operates a floating member carrying a pair of movable contacts adapted to cooperate with fixed 15 contacts in an insulated base. This floating member is usually carried by a shaft or crank journaled in suitable bearings and capable of being rocked by said handle, a spring being interposed between said shaft 20 and handle for imparting a snap motion to the shaft. In such constructions there is a certain amount of friction generated by the shaft or crank turning in its bearings. As the amount of friction created increases, 25 the amount of energy absorbed from the spring is correspondingly increased with a consequent reduction in the energy utilized in actually moving the crank and imparting a snap action thereto. In view of this, 30 a further object of the present invention is to reduce the friction generated by the contacting surfaces of the crank and its bearings to a minimum and thereby effect a maximum conservation of the energy 35 stored in the spring for the purpose of actuating the crank.

40 Again, in switch mechanism such as just outlined, there is a component of force exerted on the crank or shaft in a direction tending to press the latter against the vertically disposed portions of the walls of the crank bearings. As this also tends to detract from the efficiency of the mechanism, so far as a snap action is concerned, another 45 object of the invention is to so form the bearings in the crank supporting members as to eliminate those portions of the bearing walls which ordinarily receive the thrusts mentioned.

50 With these and other objects in view the

invention consists in certain novel details of construction and combinations and arrangements of parts, all as will hereinafter be more fully described and the novel features thereof particularly pointed out in 55 the appended claim.

In the accompanying drawings, wherein the preferred embodiment of the invention is illustrated,—

Figure 1 is a top plan view.
Fig. 2 is a section on the line 2—2 of Fig. 1.

Fig. 3 is a longitudinal sectional view, in a vertical plane, of the operating assembly of the switch removed from the insulating base.

Fig. 4 is an end elevation of the assembly shown in Fig. 3.

Figs. 5 and 6 are detail elevations of the two sides of the supporting member for the 70 crank or shaft.

Fig. 7 is an enlarged perspective of the crank or shaft; and

Fig. 8 is an enlarged perspective view 75 of actuating handle or lever.

In the preferred embodiment of the invention shown, the insulating base 18 has a recess or socket 19 therein for the reception of the operating parts of the switch. Said base is also provided with a slot 20 merging 80 into socket 19, said slot being adapted to receive the fixed contact jaws of the switch and the movable contact blade. The base is also formed with terminal seats 21 at its side and extending from said seats are leads 23 which terminate in the fixed contact members 22 and 24. Leads 23 extend transversely of the top of base 18 and downwardly into slot 20, one of said leads terminating near the top of the base in contact 85 22 while the other lead extends substantially to the bottom of said slot and forms contact 24.

While various supporting members for the blade operating crank may be devised 90 and utilized, in the present instance such members are in the form of spaced arms 26 constituting the depending portions of a bracket whose top plate 25 seats in a depression 19 formed by cutting away a portion of 100

top surface of base 18. The movable contact blade 49 is carried by the crank which is preferably made of a piece of wire bent to form outturned bearing portions 31, 31^a adapted to be journaled in bracket arms 26, the intermediate portion of the wire forming the crank 32 located between said arms. The crank portion 32 is provided with a hump 33 thereby providing a seat for one end of the compression spring 36. The wire of the crank also has a lateral projection 34 extending from the end of bearing portion 31 and a portion 35 bent back substantially parallel to said bearing portion, thereby providing a non-circular projecting end by which a non-rigid connection is made between the crank and contact blade. The coiled compression spring 36 is compressed between hump 33 of the crank and the lower end of actuating lever 39, said lower end having an edge portion 37 of semi-circular outline with a pair of shoulders 38 adjacent to such semi-circular portion. This semi-circular portion constitutes a spring seat for the upper end of spring 36, fitting rather snugly in the end thereof and preventing its lateral displacement. Preferably operating lever 39 is formed of a sheet metal member around which is molded insulating material 44, the latter being cut away as at 45 to give access to the opening 46 formed in said sheet metal member for receiving the pivot pin 47. Pivot pin 47 is secured in openings 30 in the depending arms 26 of the supporting bracket. Generally, the major portion of the structure thus far described is more fully described in my co-pending application hereinbefore referred to.

To reduce the area of the contacting surfaces of the crank and the walls of the bearings therefor in the depending arms 26, said bearings are preferably formed by providing an enlarged opening 27 in each of said arms with a shallow recess 27^a in the lower portion of the wall thereof. The recess 27^a actually constitutes the bearing surface for the crank and extends considerably less than half way around the crank shaft. Preferably, said recess is arc-shaped and approximately 90° in length between the points at which its wall merges into the sloping portions of the wall of hole 27.

As a result, a minimum amount of friction is created by the relatively moving contacting surfaces of the crank and its bearings, thereby increasing the energy actually available for actuating the movable blade of the switch. This application of maximum energy by the spring to the crank results in a noticeably snappier movement of the latter. Not only is the amount of friction reduced by decreasing the length of the bearing surface actually in contact with the crank but, with the present construction, the walls of openings 27 join the walls of

recesses 27^a at a point below the center of rotation of the crank so that the walls of openings 27 are spaced from the crank. In this way, the walls of openings 27 do not sustain any pressure from the crank shaft by reason of the horizontal thrust that is imposed on the crank shaft laterally of its center of rotation. 70

To facilitate assembly of these parts, opening 27 in one of arms 26 extends all the way to the edge thereof and to limit the rocking movement of the crank one of said arms is formed with lugs 29 which act as stops. 75

It will be appreciated that the construction of the bearing bracket and other parts of the switch may be varied without departing from the spirit of the invention as defined in the following claim. 80

What I claim is:

In a snap switch the combination of a contact blade, a rocking crank shaft circular in cross-section connected to said blade and a bracket having spaced arms each formed with an aperture constituting a bearing for said shaft, the wall of said aperture formed with an arc shaped shallow recess in the lower portion in which the said shaft is journaled, the wall of the recess terminating below the medial line of the shaft, the 90 walls of the aperture extending upwardly and outwardly away from the recess. 95
